1.990.333

POST BOX CONSTRUCTION

George S. Knickerbocker and Clyde B. Rapp,
Wayzata, Minn., assignors of thirty per cent
to James G. Bennett, Minneapolis, Minn.

Application May 2, 1932, Serial No. 608,586

8 Claims. (Cl. 232—40)

This invention relates to a mail box, and while the invention is applicable to various types of mail boxes, it relates particularly to mail boxes which are used on the rural mail routes. It is now common for the recipients of mail to have a box on a support, usually a post, at one side of the highway, so that the rural carrier can readily have access thereto. The boxes now commonly used are quite long and of considerable height. These boxes have a door at the front which opens outwardly. It is quite difficult for anyone to remove the mail in any of these boxes while in an automobile or vehicle. The door opens outwardly so that when the door is opened, it is impossible to reach to the rear of the box to secure the mail. This makes it necessary in practically all instances to leave the vehicle or automobile in order to remove the mail. This, of course, is an inconvenience, and the boxes are therefore objectionable.

It is an object of this invention, therefore, to provide a mail box structure which can conveniently be supported upon a post or other support and which is swingable forwardly when the door is opened, so that the mail will slide down to the door and may be readily removed without the necessity of reaching an arm or hand into the box.

30 It is a further object of the invention to provide a mail box structure comprising an elongated box supported on and extending transversely of a post, said box normally being in horizontal position and having a door closing its front end, said box being swingable upwardly and forwardly about a transverse axis when said
35 door is opened.

It is more specifically an object of the invention to provide a mail box structure comprising a post, a bracket pivoted to said post, a box carried by said bracket, the axis of said pivot extending transversely of said box below the same, a door closing the front end of said box and pivoted thereto, and guiding means carried by said door and cooperating with guide means at the sides of said post so that when said door is opened, said box is swung forwardly of said post.

It is still further an object of the invention to provide such a structure as set forth in the preceding paragraph, said door having a flange thereabout and means on said door comprising bars with arcuate slots therethrough, the guiding means on said post comprising pins projecting through said slots.

It is also an object of the invention to provide a mail box structure comprising a post, an elongated box mounted thereon and swingable for-

wardly about a transverse axis, a door pivoted to said box closing the front end thereof and swingable to open position when said box swings forwardly, a signal carried on said box movable to horizontal and vertical positions, and means on said door for moving said signal to vertical position.

These and other objects and advantages of the invention will be fully set forth in the following description made in connection with the accompanying drawing, in which like reference characters refer to similar parts throughout the several views and in which:—

Fig. 1 is a view in side elevation of the mail box and support;

Fig. 2 is a view in front elevation of the parts shown in Fig. 1;

Fig. 3 is a view in side elevation showing the box in its tilted and open position, some parts being broken away and others shown in vertical section.

Fig. 4 is a perspective view showing the support and bracket for the box;

Fig. 5 is a perspective view showing the signal structure used, and

Fig. 6 is a perspective view similar to Fig. 5, showing the signal in a different position.

Referring to the drawing, a support 10 is shown, and while this support may take various forms, in the embodiment of the invention illustrated it is shown as a vertical post rectangular in cross section, which preferably will be made of wood. A bracket 11 is secured to post 10 and as shown in Fig. 4, this bracket comprises a vertical strap-like portion extending substantially centrally

like portion extending substantially centrally along the front vertical face of post 10, said bracket having another portion 11a extending transversely and rearwardly across the top of said post. Bracket 11 also has arms 11b extending outwardly from each side thereof on the top of the post adjacent its front edge and having downwardly depending ends 11c extending vertically. Bracket 11 is secured to post 10 by a plurality of screws 11e having their heads countersunk in said bracket. The lower front end of bracket 11 is provided with an eyelet or lug 11d which is embraced by spaced lugs 12a on another bracket 12 in the shape of a strip or bar, the same being bent at right angles intermediate its ends and adapted to extend across the top of bracket 11 with its upper portion or arm 12b in horizontal position. A headed pivot 13 extends through lugs 12a and 11d and bracket 12 is thus pivoted to bracket 11. An elongated box 14 having a flat bottom, vertical sides and a semi-cylindrical top, 55

as well as a vertical rear end, is secured to portion 12b of bracket 12 by suitable rivets 14a so that said box when in normal position extends horizontally across the top of post 10 with its front end substantially flush with the front of said post. The box 14 is provided with a door 15 having spaced ears or lugs 15a at its lower edge received between similar lugs 15b at the front edge of the box, said lugs 15b and 15a receiving a suitable pintle 16 so that said door 15 is pivoted to the box 14. Door 15 is adapted to close the front end of box 14 and said door has a flange 15b extending thereabout adapted to surround the front end of box 14. The door 15 has secured to its sides and projecting therefrom, preferably from the sides of flange 15b as shown, bars 15c which are shown as curved and provided with arcuate slots 15d, said slots having at their lower or inner ends recesses or branches 15e. Headed members 17 such as headed and nutted bolts, extend through apertures in portions 11c of bracket 11 and through the slots 15d on the bars 15c.

The box 14 has a signal 18 mounted thereon, shown as generally in the shape of a flag, which signal is pivoted by a pivot 19 to a small bracket 20 secured to box 14. The door 15 has secured in the flange 15b thereof a pair of headed screws or rivets 21 having their heads spaced from said flange and extending through a slot 22a in a slideable handle or member 22, the latter being curved downwardly at its outer end. Member 22 has thereon a cam 22b which is wedge-shaped at its front end and adapted to engage signal member 18, the latter having a tapered bend or trough-shaped portion 18a formed in the lower portion thereof.

In operation the box normally occupies the position shown in Fig. 1, the same at this time being substantially horizontal and bar 12b of bracket 12 extends horizontally in engagement with portion 11a of bracket 11. The door 15 at this time is closed and the members 17 are at one end of slots 15d. When it is desired to have access to the mail box, the operator pulls outwardly on the handle member 22 and door 15 swings about its pivot 16 and as the door swings open, the bars 15c move relatively to the fixed members 17 so that the bracket 12 and the box 14 swing about pivot member 13. When the parts are in the position shown in Fig. 3, members 17 move into the recesses 15e of the slots 15d so that the box will remain in the position shown in Fig. 3, members 17 at this time engaging the sides of the recesses 15e. It will be seen that the inner side of the door is now substantially flush with the bottom of the box 14 and the parts are at such an angle that any mail matter in the box will slide by gravity down onto the door 15. Such matter will be retained by the flange 15b and the same can readily be obtained by the operator without the necessity of reaching far into the box. When the box is to be moved to normal position, the operator merely moves the handle member 22 upwardly and the bars 15c again move relatively to member 17 and the parts again move to the position shown in Fig. 1 with the door 15 closed.

The signal 18 is used to indicate to the recipients of the mail or to the post carrier, that there is mail matter in the box. Should the operator desire to lift the signal, he will merely push inward upon member 22 and cam 22b will engage member 18 and swing the same up to vertical position as shown in Fig. 5. If it is desired to have

the signal in horizontal position, handle 22 can be pulled outwardly relatively to the members 21 without pulling it far enough to open the door 15.

From the above description it is seen that applicant has provided a very simple and efficient structure of mail box. With such a structure it is easy and convenient for the operator, even if located in a vehicle or automobile, to operate the box and to readily secure the mail therein. The box, of course, can be vibrated somewhat if any mail should incline to stick and not slide down readily. It is also quite easy to place mail in the box. The box is very easily opened and closed and this requires very little effort on the part of the operator. The parts of the device are simple and rugged and comparatively few in number. The structure can therefore be easily made and made at comparatively little expense. The device has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:—

1. A mail box structure having in combination, a supporting post, an elongated box swingably mounted on said post about a horizontal axis extending transversely of said box, a door for closing the front of said box and pivoted to said box, guide bars secured to the sides of said door, guide members at the sides of said post for guiding and holding said bars as said door swings to open position and means on said door adapted to be grasped to swing said door and box.

2. A mail box structure having in combination, a support, a member pivoted to said support, a box carried by said member normally disposed in horizontal position, a door for closing the front end of said box and pivoted thereto, guide bars secured to said door having arcuate slots therethrough, members projecting from the sides of said support and disposed in said slots for guiding said door as the same is opened, said door being constructed and arranged to be opened and to swing said box forwardly into inclined position with its rear end elevated.

3. A mail box structure having in combination, a supporting post, a bracket pivoted to said post below the top thereof and about a horizontal axis, an elongated box carried by said bracket extending transversely of said axis, a door pivoted at its lower edge to the front of said box adjacent the front of the bottom of said box and adapted to close the front end of said box when said box is in normal horizontal position, members carried by said door having arcuate slots therein, means projecting from the sides of said post extending through said slots, said slots having recesses at their ends into which said means are movable when said door is in open position, and a handle for swinging said door to open position and for swinging said box about said axis, said door substantially aligning with the bottom of said box when in open position and said box swung to inclined position with its rear end elevated, whereby the contents of said box may slide downwardly to said door.

4. The structure set forth in claim 3, said door having a flange thereabout for retaining mail.

sliding thereto, said members projecting from said flange.

5. A mail box structure having in combination, a supporting member, a member pivoted to one side of said supporting member about a horizontal axis, a box secured to said member having its longitudinal axis extending transversely of said axis, a door for closing the front of said box extending substantially vertically when in closed position and hinged at its lower end to said box at the bottom thereof, said box and member being swingable forwardly about said horizontal axis to inclined position to elevate the rear end of said box, a member secured to said door, and stationary means engaging said last mentioned member to limit movement of said door and box when said door is swung forwardly to open position and said box is simultaneously swung forwardly to said inclined position, said door moving to open position substantially alined with the bottom of said box.
6. A mail box structure having in combination, a support, an elongated box mounted on said support to swing about a horizontal axis adjacent the front and bottom of said box, said box having its longitudinal axis extending transversely of said horizontal axis and being movable to inclined position with its rear end elevated and swinging forwardly on said support, and a door hinged at its lower end to the front of said box adjacent the bottom thereof adapted to close the forward end of said box when said box is in horizontal position, and swingable to open position with said box when said box swings to inclined position with its rear end elevated so that the plane of said door is substantially alined with the plane of the bottom of said box.

7. A mail box structure having in combination, a support, a member pivoted to said support about a horizontal axis, a box rigidly carried by said member having an open front end, said axis extending substantially at right angles to the longitudinal axis of said box and disposed at the front of said box, said box normally being disposed in a horizontal position but swingable with said member about said horizontal axis to inclined position with its rear end elevated and a door for closing said front end of said box pivoted thereto so as to swing into substantial alinement with the bottom of said box whereby when said box is so inclined the contents will slide down onto said door.

8. A mail box structure having in combination, a support, a member pivoted to one side of said support about a horizontal axis, a box rigidly carried by said member with its longitudinal axis extending transversely of said axis and swingable with said member toward said side to inclined position with its rear end elevated, a door for closing the front end of said box and pivoted on a horizontal axis at its lower edge to the front of the bottom of said box and swingable outwardly, guide means on said support, and means on said door cooperating with said guide means and movable relatively thereto as said door is swung to open position and said box is swung to said inclined position to limit the movement of said box and door so that said door extends in substantially the same plane as the bottom of said box so that mail will slide out of said box onto said door.
